[57] CLAIM

The ornamental design for a truck bed tray, as shown and described.

DESCRIPTION

FIG. 1 is a top perspective view of the truck bed tray of our invention;

FIG. 2 is a side elevational view thereof;

FIG. 3 is a top plan view thereof;

FIG. 4 is front elevational view thereof;

FIG. 5 is a bottom plan view thereof; and,

FIG. 6 is rear elevational view thereof.

FIG. 7 is a top plan view of an alternative embodiment of the truck bed tray of our invention, the side elevational view being shown in FIG. 2, the front elevational view being shown in FIG. 4, and the rear elevational view being shown in FIG. 6; and,

FIG. 8 is a bottom plan view thereof.
